DETACHABLE SUPPORTING STEP
Linford G. Linaberry, Sr., Gladwin, Mich.
Filed June 4, 1958, Ser. No. 739,712
1 Claim. (Cl. 182—187)

This invention relates to supporting step constructions of the kind adapted for attachment to highway signposts or the like for supporting a workman at any desired height above the ground. More particularly, the invention pertains to detachable supporting steps having no moving parts and which are capable of being securely clamped on an upright post at any desired height above ground level.

Posts of the kind generally used to support highway or the like signs are generally of two types, namely, cylindrical posts or sheet metal posts bent to substantially channel shape. In either event, such posts generally are of substantial length so as to enable the post to be inserted firmly into the ground and yet support the sign at sufficient height above ground level that the sign will not be obscured by parked vehicles. Due to the distance the sign is supported above ground level, it frequently is difficult for workmen to stand on the ground and reach the fastening means which connect the sign to the post in the event it is desired to change the sign. Consequently, it is desirable that the workman be provided with a device of some kind for enabling him to reach the top of the sign.

From time to time it becomes necessary to remove a sign and its signpost from a long established location. Where a signpost has been embedded in the ground for a long period of time, it sometimes is extremely difficult to loosen the signpost from the earth, even though a mechanical or power signpost puller device is used. However, if the signpost can be worked back and forth prior to the application of pulling force, the removal of the signpost from the ground is greatly facilitated.

Frequently, highway signposts become bent or twisted, due to high winds or other causes, but many such signposts may continue to be used if they can be straightened. Preferably, the signposts should be straightened without requiring their removal from the ground and it has been customary heretofore for workmen to utilize a wrench or the like in the straightening operations.

An object of this invention is to provide a detachable step construction which is adapted for attachment at any desired level to a signpost of predetermined configuration and which may be rigidly clamped to the post so as to support the weight of a workman.

Another object of the invention is to provide a detachable step construction which may be clamped to a signpost of particular configuration and support the weight of a user as he rocks the signpost back and forth to loosen it in the ground.

A further object of the invention is to provide a detachable step construction of the kind referred to which contains no moving clamp parts, but which is capable of being attached rigidly to a signpost so as to provide safe support for a workman.

Still a further object is to provide a device of the character described which is capable of use in straightening bent or twisted posts and which includes adjustable means for enabling the user to apply considerable force to the post.

Other objects and advantages of the invention will be pointed out specifically or will become apparent from the following description when it is considered in con-

2

junction with the appended claim and the accompanying drawings, in which:

FIGURE 1 is a rear elevational view of a typical sign and signpost currently in use and showing a detachable step constructed in accordance with one embodiment of the invention mounted on the signpost;

FIGURE 2 is a top plan view of the adjustable step shown in FIGURE 1, the post being shown in section;

FIGURE 3 is a front elevational view of the step shown in FIGURE 2;

FIGURE 4 is a view similar to FIGURE 2, but showing a modified form of the invention;

FIGURE 5 is a view similar to FIGURE 3, but illustrating the step shown in FIGURE 4; and

FIGURE 6 is an end view of a step having an adjustable lever arm mounted thereon.

A detachable step formed in accordance with the embodiment of the invention shown in FIGURES 1, 2 and 3 is designated generally by the reference character S and comprises a body member 1 and preferably composed of an angle bar having a generally horizontal top flange 2 and a substantially vertical side flange 3. Adjacent to one end of the body member 1 is welded or otherwise suitably secured to the upper surface of the top flange 2 a clamping element 4. The element 4 includes a portion 5 which projects laterally from the body and overhangs the vertical flange 3. The clamping element 4 also is provided along its inner edge with a substantially right-angular notch 6, the apex *a* of the notch being located substantially flush with the outer surface of the side flange 3 and the outer portion of the notch terminating in a point *b*. A second clamping element 7 is welded or otherwise suitably secured to the lower surface of the flange 3 in vertically spaced relation to the element 4 and is arranged to project laterally in substantially the same direction as the clamping element 4. The element 7 is provided with a surface 8 which slopes inwardly and away from the element 4 from a point *c*, but which faces the notch 6 in the clamping element 4 for a purpose presently to be pointed out. At the end of the body member 1 which is remote from the clamping element 4 is welded or otherwise suitably secured a crossbar or enlargement 9 which conveniently may comprise an angle piece having an upper, substantially horizontal flange 10 and a vertically depending flange 11. The crossbar 9 extends a substantial distance on either side of the body member 1 so as to provide a support for both feet of a workman.

Referring now to FIGURES 1 and 2, the kind of signpost 13 with which the supporting step S is adapted for use preferably comprises a sheet metal member having a central portion 14, each side edge of which is bent to form with the portion 14 a substantially channel shaped element terminating on either side in flanges 15. The upper end of the post 13 may be provided with a plurality of openings 16 for the accommodation of screws or bolts 17 by means of which one or more signs 18 may be removably secured to the post, and the lower end of the post 13 may be pointed, if desired, to facilitate its being driven into the ground 19.

Signposts of the kind shown at 13 are substantially uniform throughout the country, so supporting steps S may be mass-produced without fear that they will not fit on all posts of the kind shown at 13. When assembling the various elements of the step 1, the clamping elements 4 and 5 should be spaced longitudinally of the body member 1 a distance such that the space between the apex *a* of the notch 6 and the corresponding point *d*

of the clamping surface 8 corresponds substantially to the width of the post 13. As will be evident from FIGURES 1 and 2, the distance between parallel vertical planes passing through the points *a* and *d* is greater than the distance between parallel vertical planes passing through the points *b* and *c* of the clamping elements 4 and 7, respectively. The reason for this construction is to enable the outer edges *b* and *c* of the clamping surfaces to overlie the flanges 15 of the post and prevent inadvertent separation of the step S from its post. The construction and arrangement of the parts 5 and 7 are such, however, that the step S may not be attached to the post when the step is in a horizontal position.

To assemble the step S on a post 13, it is necessary that the step be rocked clockwise, as viewed in FIGURE 1, from the full line position to the chain line position. In this position of the step, the flanges 15 of the post 13 may be inserted between the clamping element portions 5 and 7 because the straight line distance between the points *b* and *c* is so selected as to be greater than the width of the post 13. When the post has been received between the clamping element sections 5 and 7 and the flanges 15 of the post bear against the vertical wall 3 of the body member, the step may be adjusted longitudinally of the post and, at the desired location above ground level, be rocked counterclockwise so as to cause the clamping surfaces 6 and 8 to clamp against the sides of the post as is indicated in FIGURES 1 and 2. In this connection, the distance between parallel vertical planes passing through the points *a* and *d* should be so selected as to correspond substantially to the width of the post 13 so that in clamped condition the upper surface of the body portion 2 will be substantially horizontal.

When the step has been clamped in adjusted position, a workman may stand on the crossbar 9 to gain access to the screws or bolts which hold the sign 18 on the post 13 or he may support himself on the step S and grasp the post 13 while shaking the latter back and forth to loosen the post in the ground so as to facilitate its removal either manually or by a post-pulling device.

In FIGURES 4 and 5 is shown a step S' which is generally similar to the step S except for minor variations to enable it to be attached to a cylindrical or tubular sign support 21. In the modified construction, the body portion 22 comprises an angle bar similar to the bar 2 in that it includes an upper, horizontal flange 23 and a vertical, side flange 24. To the upper surface of the flange 23 and adjacent to one end of the latter is welded or otherwise suitably fixed a clamping bar 25 having a portion 26 which projects laterally beyond the side flange 24.

To the lower surface of the side flange 24 in vertically spaced relation to the element 25 is welded a laterally projecting bar 27 to which is welded or otherwise suitably secured a clamping element 28 having a sloping clamping surface 29 terminating in an outer point 30. The clamping element 25 includes a notch 31, the surfaces of which constitute clamping surfaces 32 and 33 terminating in an outer point 34. The distances the clamping elements 26 and 28 project laterally from the side flange 24 should be so selected that the points 30 and 34 are spaced from the flange 24 a distance greater than the radius of the post 21 and the longitudinal spacing of the clamping elements along the body portion 22 should be so selected that the distance between parallel planes passing through the points 30 and 34 is less than the diameter or width of the post 21. The step S' may be completed by the welding of an enlargement or crossbar 35 to the end of the body portion 22 remote from the clamping elements and the enlargement 25 conveniently may comprise an angle bar having an upper flange 36 and a vertical flange 37 similar to the corresponding elements of the enlargement 9.

Although the distance between parallel planes passing through the points 30 and 34 is less than the diameter of the post 21, the straight line distance from point to point

is greater than the diameter of the post. Accordingly, the step 20 may be canted, as is shown in chain lines in FIGURE 5, so as to permit the post 21 to be received between the clamping elements 26 and 28 and with the points 30 and 34 located outwardly of the post. Thereafter, the step may be rocked counterclockwise, as viewed in FIGURE 5, so as to bring the clamping surfaces of the clamping elements 26 and 28 into clamping engagement with opposed sides of the post 21 whereupon the step 20 will be rigidly clamped on the post 21.

To adjust either of the disclosed steps S or S' longitudinally of their respective posts, it is necessary only to rock the steps to such positions that the clamping surfaces of the respective clamping devices are free of the posts' edges. When the steps have been adjusted to a desired position, they may be released by the workman and will automatically clamp themselves on their respective posts because of their natural tendency to rock in a counterclockwise direction as is viewed in the drawings. This tendency on the part of the steps is caused partly by the provision of the supporting enlargements 9 and 35 and partly because the clamping devices of each step are located more closely adjacent to one end of the unit than to the other end.

The removal of either supporting step from its associated signpost may be effected quite simply merely by reversing the procedure followed in mounting the step on the post.

Referring now particularly to FIGURE 6, either or both of the steps S and S' may include a lever arm or rod 40 slideably mounted for movement parallel to the longitudinal axis of the respective body member in a pair of brackets or ears 41 having openings therein to accommodate the arm. The arm 40 normally is so located that its ends do not extend beyond the ends of the body member, but the rod is shiftable longitudinally so as to enable it to project beyond one end or the other of the step. The rod may be prevented from being separated from the step, if desired, by a cotter pin or the like 42 located substantially at its middle.

When a post is to be straightened or untwisted, the step S or S' is clamped to the post in the manner previously described and the lever arm 40 extended from one end of the step so as to provide an extension whereby considerable force may be applied to the post to straighten or untwist it.

The disclosed embodiments are representative of presently preferred embodiments of the invention, but are intended to be illustrative rather than definitive thereof. The invention is defined in the claim.

I claim:

A detachable supporting step for attachment to an upright post, said step comprising a body member having a substantially flat, planar face defined by an upper edge and a lower edge spaced from said upper edge; a first clamping element connected to said body member adjacent one of said edges and extending laterally from said face of said body member, said element having a straight edge converging toward said one face of said body member and forming a V with said one face, the apex of said V being located at said one face of said body member; a second clamping element connected to said body member adjacent the other of said edges and extending laterally from said one face of said body member in the same general direction as said first clamping element, said second element also having a straight edge converging toward said one face of said body member and forming a V with said one face, the apex of the second mentioned V also being located at said one face of said body member, said elements being spaced from one another longitudinally of said body member a distance such that the distance between said apices corresponds substantially to the width of the post on which said step is to be mounted, the distance between the ends of said elements remote from said one face of said body member being less than

the width of the post on which said step is to be mounted; bracket means carried by said body member on the opposite side of said face; and a lever arm slideably supported by said bracket means to provide an extension of said body member.
